(57) **CLAIM**

The ornamental design for a solid state relay, as shown and described.

DESCRIPTION

FIG. 1 is a top, front, and left side perspective view of a solid state relay showing our new design;

FIG. 2 is a bottom, front, and right side perspective view thereof;

FIG. 3 is a front view thereof;

FIG. 4 is a left side view thereof;

FIG. 5 is a right side view thereof;

FIG. 6 is a top view thereof;

FIG. 7 is a top, front, and left side perspective view thereof, shown in an alternate position of use;

FIG. 8 is a bottom, front, and right side perspective view thereof, shown in the alternate position of use;

FIG. 9 is a front view thereof, shown in the alternate position of use;

FIG. 10 is a left side view thereof, shown in the alternate position of use;

FIG. 11 is a right side view thereof, shown in the alternate position of use; and,

FIG. 12 is a top view thereof, shown in the alternate position of use.

The dashed broken lines in the figures show portions of the solid state relay that form no part of the claimed design. The dot-dashed broken lines in the figures depict the bounds of the claim and form no part thereof.
